(57) **CLAIM**

The ornamental design for a catheter including power injectable lumen, as shown and described.

DESCRIPTION

FIG. 1 is a perspective view of a catheter including a power injectable lumen, lined for color;

FIG. 2 is another perspective view thereof;

FIG. 3 is a left side elevation view thereof;

FIG. 4 is a top view thereof;

FIG. 5 is a front elevation view thereof, shown at a larger scale;

FIG. 6 is a rear elevation view thereof, shown at a larger scale;

FIG. 7 is a right side elevation view thereof; and,

FIG. 8 is a bottom view thereof.

The broken line showing of parts of the drawings is included for the purpose of illustrating use and environment and forms no part of the claimed design.

1 Claim, 5 Drawing Sheets
